CLAIM

The ornamental design for a rail support fitting for a double post, rail fence unit or the like, substantially as shown and described.

DESCRIPTION

FIG. 1 is a perspective view of a rail support fitting for a double post, rail fence unit, or the like showing my new design;

FIG. 2 is a front elevational view thereof, and the rear view thereof being substantially a mirror image of the front elevational view;

FIG. 3 is a bottom plan view thereof;

FIG. 4 is a top plan view thereof;

FIG. 5 is a side elevational view thereof, and the opposite side elevational view being substantially a mirror image thereof.

FIG. 1

FIG. 4

FIG. 2

FIG. 5

FIG. 3
